[57] CLAIM

The ornamental design for a combination floss holder,
key chain fob and dental appointment reminder, sub-
stantially as shown.

DESCRIPTION

FIG. 1 is a top plan view of a combination floss holder,
key chain fob and dental appointment reminder show-
ing my new design;

FIG. 2 is a side elevation thereof;

FIG. 3 is a bottom plan view thereof; and

FIG. 4 is a cross sectional view taken on the line 4—4 of
FIG. 1.
